US0D1044800S

(12) **United States Design Patent** (10) Patent No.: **US D1,044,800 S**
(45) Date of Patent: ** Oct. 1, 2024

(54) **SMART HOME HUB**

(71) Applicant: **AMBIT MICROSYSTEMS (SHANGHAI) LTD.**, Shanghai (CN)

(72) Inventor: **Yu-Ying Chou**, New Taipei (TW)

(73) Assignee: **AMBIT MICROSYSTEMS (SHANGHAI) LTD.**, Shanghai (CN)

(**) Term: **15 Years**

(21) Appl. No.: **29/811,878**

(22) Filed: **Oct. 18, 2021**

(51) LOC (14) Cl. **14-02**

(52) U.S. Cl.

USPC **D14/358**

(57) **CLAIM**

The ornamental design for a smart home hub, as shown and described.

DESCRIPTION

FIG. 1 is a rear, left and bottom perspective view of a smart home hub;

FIG. 2 is a front, right and top perspective view of a smart home hub;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The even broken lines illustrating portions of the smart home hub form no part of the claimed design.

1 Claim, 8 Drawing Sheets
